Patented 25th October 1853

DESIGN FOR REGISTER.

Joseph A. Read, of Philadelphia, Pa.

Assignor to

DES 606

William W. & Charles M. Atkins.

Letters Patent No. 606. — Dated Oct. 25th, 1853.

The schedule referred to in these Letters Patent, and making part of the same.

To all whom it may concern:

Be it known that I, Joseph A. Read, of the City and County of Philadelphia, and State of Pennsylvania, have produced a new and original Design for furnace Registers, and I do hereby declare that the following is a full, clear, and exact description of the same, reference being had to the annexed drawing forming part of this specification, which represents a front elevation of the Register.

The front, which is made up of the slide a and plate b, has, when the register is closed, the appearance of a series of vertical panels, rounded at top and bottom; those of the slide bearing the foliage f and scrolls d, in bas-relief, arranged and having the configuration set forth in the drawing. These panels have at their sides the reeds c, around which is the foliage e. From the extreme foliage bands g issue the hoops h and branches i, which form the tops and bottoms of the series of panels.

The panels m of the plate b, are sunken, and are ornamented in bas-relief by the foliage n, and figures s, having the arrangement and configuration set forth in the drawing.

What I claim as my production and desire to secure by Letters Patent, is

The design, configuration, and arrangement of the ornaments in bas-relief on the slide a and plate b, as set forth in this specification, and the annexed drawing.

In testimony whereof, I have hereunto signed my name before two subscribing witnesses.

Witnesses,

C. Drayer,
George Gamber.

Joseph A. Read.
